UNITED STATES PATENT OFFICE

2,550,903

MATERIAL MEASURING AND DISPENSING DEVICE

Samuel H. Berch, Beverly Hills, Calif.

Original application November 28, 1945, Serial No. 631,331. Divided and this application May 15, 1947, Serial No. 748,203

6 Claims. (Cl. 226—103)

1

This invention relates to packaging devices, and particularly pertains to a material measuring and dispensing device and is a division of my application entitled "Packaging Machine for Ice Cream and the Like," Serial No. 631,331 filed by me November 28, 1945, and since issued as U. S. Letters Patent No. 2,500,922.

The present invention is applicable for use in packaging various products which are in a semi-fluid condition when packaged, but the invention has particular value in the packaging of ice cream to be dispensed in restaurants, catering establishments, soda fountains, and at retail. In dispensing ice cream it has been found that the sale of ice cream in bulk is unsatisfactory for the reason that the ice cream does not maintain a desired consistency and in addition will shrink. It is also common knowledge that the uniform scooping of ice cream from a bulk supply depends upon the skill and care of the dispenser. An additional disadvantage in dispensing from bulk is that water may be carried into the container with the scoop so that ice particles are formed, which render the ice cream unsaleable, and sanitary conditions attendant to the use of a scoop in a bulk container are not desirable. Due to these conditions the merchandiser of ice cream can never be certain of making a fixed profit since the profit may vary. This tends to promote a practice on the part of the merchandiser to skimp in the servings of ice cream or to substitute cheaper grades of ice cream from those which the character of his trade expects. From the merchandising standpoint there is also the objection that advertising does not create a sufficient demand for a particular advertised brand, since in sales from bulk, at least, the retail purchaser cannot identify the product from its appearance. It is therefore desirable to provide a means for packaging ice cream which will utilize a simple and inexpensive package such as disclosed in my co-pending application entitled "Carton for Ice Cream and the Like," filed October 31, 1944, and bearing Serial No. 561,235, said application since issuing as U. S. Letters Patent No. 2,443,530, said package permitting merchandise to be identified and sold at a fixed profit without reference to the loss by shrinkage, contamination or unsanitary conditions. In order to accomplish these results and to meet competition of bulk ice cream manufacturers it is necessary to provide automatic means by which carton blanks may be folded, filled and closed, and it is the principal object of the present invention to provide a machine for packaging ice cream and the like in-

2

volving the use of carton blanks as disclosed in the aforesaid application and in which machine blanks are consecutively withdrawn from a magazine, carried to forming means, and then consecutively to filling and closing stations, whereby the packaging may be accomplished rapidly and in a sanitary full automatic operation.

The present invention is concerned with measuring and dispensing means for receiving material in a fluid state from a constant supply, thereafter measuring a predetermined amount of said material and discharging the same into a receptacle, the receiving and discharging operations taking place simultaneously while the measuring and dispensing means is intermittently driven.

The invention is illustrated by way of example in the accompanying drawings in which:

Figure 1 is a view in plan showing the complete machine as designed to form, fill and discharge four containers in one unit of operation.

Figure 2 is a view in vertical section and elevation as seen on the line 2—2 of Fig. 1 and shows the driving mechanism for the structure.

Fig. 3 is a view in horizontal section and elevation as seen on the line 3—3 of Fig. 2 and shows other details of the driving mechanism.

Fig. 4 is a view in transverse section through the machine as seen on the line 4—4 of Fig. 1 and shows the ice cream measuring and dispensing device at the beginning of an ice cream dispensing step.

Fig. 5 is an enlarged detail view of an upper portion of Fig. 4 at the completion of an ice cream dispensing step.

The present measuring and dispensing means is used in the general combination illustrated in the aforementioned drawings and will be explained in this connection although the invention is particularly disclosed in Figs. 4 and 5.

In the drawings, a carton blank is shown with which the present invention is particularly concerned although it is to be understood that the mechanism involving the present invention may be adapted for use with blanks of other designs. The carton blank, here indicated at 10, is designed to form a cube-shaped container, the details of which are specifically set forth in my U. S. Letters Patent No. 2,443,530 above referred to. Generally considered, the present invention is concerned with a machine equipped with magazines to receive a quantity of the blanks 10, to thereafter fold and form said blanks, and to then carry the folded cartons to means by which measured quantities of ice cream may be dis-

charged into the cartons in register therewith and after which the carton may be completely closed and its parts interlocked to hold the contents of the carton in a closed and sealed condition. It is understood that while the invention is described as being used with ice cream that other products might be used if desired, and it is to be further pointed out that the means for measuring and filling the cartons may be employed with other machinery and with other products than those here shown.

In the drawings, 11 indicates a base structure. This structure is defined by a housing having opposite end walls 12 and 13, opposite side walls 14 and 15, a floor 16, and a top 17. For convenience, the top is substantially at table height. Disposed above the top is a plurality of carton blank magazine units 18, adjacent to which are carton folding and forming units 19. There are also mounted above the top 17 a plurality of product measuring and dispensing units 20 and a plurality of carton closing units 21. The carton magazine units 18 and the carton closing units 21 are disposed in the path of travel of a conveyor chain 22 and along the straight run 22^a thereof. The folding and forming units 19 and the measuring and dispensing units 20 are disposed along the other parallel straight run of the conveyor chain 22, as indicated at 22^b. The conveyor chain 22 is led around sprocket wheels 23 and 24 adjacent to the opposite ends of the base structure 11. These sprockets lie in a horizontal plane parallel to the top 17 of the base. The sprocket 23 is an idler sprocket mounted upon a vertical shaft 25. The sprocket 24 is a driven sprocket mounted upon a vertical drive shaft 26. The shaft 26 is supported in bearings 27 and 28 and is driven intermittently through a mechanism to be hereinafter described.

A power unit for driving the shaft 26 and the other parts of the machine comprises an electric motor 29 mounted within the base structure upon a platform 30. The motor shaft 31 carries pulleys 32 and 33. The pulley 32 receives a belt 34 which is led around a pulley 35 of a compressor 36. The pulley 33 receives a belt 37 which leads around a pulley 38 mounted upon a horizontally disposed jack shaft 39. This shaft is mounted in bearings 40 resting upon the floor 16 of the base structure at approximately the center thereof. The jack shaft also carries a pulley 41 receiving a belt 42. The belt 42 leads around a pulley 43 mounted upon a jack shaft 44. The jack shaft 44 is suitably supported in bearings 45 carried by a gear box 46. The gear box 46 is also fitted with bearings 47 through which a vertical shaft 48 extends and by which it is rotatably supported. Mounted upon the shaft 48 is a worm wheel 49 in mesh with a worm gear 50 which is carried upon a jack shaft 44. The vertical shaft 48 is rotatably supported at its opposite ends by bearings carried by the floor and top sections of the base. Mounted upon the shaft 48 at a point beneath the gear box 46 is a disc 51 carrying a pin 51'. The pin 51' is adapted to engage the slots of a Geneva cam 52 which is mounted upon a cam shaft 53. The shaft 53 also carries a relatively large driving gear 231 which is in mesh with one of a series of gears 230 mounted upon vertical shafts 230'. The shafts 230' are mounted in bearings secured to the floor 16. A vertical shaft 56 is rotatably mounted in a bearing carried by the bottom wall 16 of the housing. A gear 55 is freely mounted on the shaft 56 and is driven by a gear 54 mounted upon shaft 46. Pivoted

to the gear 55 is a rack bar 58 which is secured to a pivot pin 59. The rack bar extends horizontally and is held in mesh with a pinion 60 which is freely rotatable upon the drive shaft 26. This pinion is fixed to a disc 61 on the drive shaft 26. At a point in the margin of the disc 61 is a notch having a square shoulder 62. Disposed directly beneath the disc 61 is a disc 63. This disc is keyed to the drive shaft 26 and carries a pawl 64 which may fall into the notch and encounter the shoulder 62. A spring 65 urges the pawl 64 inwardly so that it will bear against the periphery of the disc 61. A notch 66 is formed in the circumferential edge of the disc 63 and is engaged by a pin 67. The pin 67 is carried at one free end of a bell crank 68. This bell crank is pivoted upon a vertical pivot shaft 69 carried in a suitable bearing on the floor of the base. The other arm of the bell crank 68 extends horizontally and terminates in an arcuate portion 70 which occurs beneath the gear 55. This arcuate portion is concentric with the axis of the shaft 56 and when the gear 55 rotates in a clockwise direction a pin 71 thereon will engage the arcuate portion 70 of the bell crank 68 and withdraw the lock pin 67 from the notch 66 in the edge of the disc 63. A spring 72 is fastened to the bell crank and tends to urge the pin 67 against the periphery of the disc 63. A shackle structure 73 embraces the rack 58 and is pivoted upon the shaft 26 so that as the rack reciprocates and oscillates it will be maintained in constant mesh with the pinion 60. By this arrangement the conveyor chain 22 will be driven a predetermined distance at each driving impulse and will be locked against movement in the pause therebetween.

Provided on the chain 22 at equal spaced intervals along the length thereof is an endless series 40 of individual molds 75 within which cartons made from the blanks 10 are to be placed and filled. The members 75 are substantially U-shaped and have a bottom wall 76 and parallel vertical walls 77. The vertical walls extend in planes normal to the longitudinal center of the sprocket chain 22. The sides of the molds 75 are open.

The measuring and dispensing units 20 involve novel means for measuring quantities of semi-solid material and for discharging it in predetermined measured quantities to a container. The structure is simple and may be made easily from stainless steel so that the parts may be quickly removed, separated and sterilized when required. 55 Each of the measuring units comprises an outer cylindrical shell 208. This shell is secured to a horizontal floor plate 209 which is disposed above the path of travel of the conveyor chain 22 and is parallel to the top wall 17 of the base structure. The shell 208 is formed with a bottom wall 210. Valve ports 211 and 212 are formed through the bottom wall 210 and the plate 209. These ports are spaced equally from the center of the shell upon diametrically opposite sides thereof and with their central axes in the same plane as the vertical center of the shell. This plane is normal to the path of travel of the conveyor chain 22. The center line of the valve port 212 is in vertical alignment with the center of the run of conveyor chain 22 which passes beneath the plate 209. The upper end of the cylindrical shell 208 is open and receives a measuring valve rotor 213. This valve rotor is formed with a plurality of measuring cylinders 214 and 215. The measuring cylinders extend parallel to each other

and to the central axis of the cylindrical shell 208 and are designed to register with the valve ports 211 and 212. Mounted to reciprocate in each of the cylinders 214 and 215 are pistons 216, each of which carries a plunger rod 217 at its upper end. These plunger rods each extend through a packing gland 218. The lower ends of the cylinders 214 and 215 are of the same diameter as the ports 211 and 212. Thus when the lower opened ends of the cylinders register with the valve ports 211 and 212 a clear and unobstructed passageway will be formed. Secured beneath the valve port 211 is a manifold conduit 219 which extends horizontally and is formed with a plurality of lateral connections 220, one of which is in direct communication with each of the valve ports 211. As shown in Fig. 5 of the drawing the conduit 219 is of larger cross-section than the connections 220. A feed pipe 221 connects with the manifold, as shown in Fig. 1 of the drawing, and this in turn leads to a source of ice cream supply from which ice cream is delivered under pressure in a semi-fluid state to the machine. The opposite ends of the manifold are provided with removable plugs 222 which permit free access to the manifold so that the interior thereof may be cleaned and scalded when desired. Disposed beneath the valve port 212 is a nozzle 223. This nozzle has a discharge end of reduced diameter so that the ice cream forced from a measuring cylinder will be discharged into a carton disposed therebeneath. Mounted upon the upper end of each of the measuring valves 213 is a gear 224. This gear extends around the perimeter of the portion of the valve which projects above the cylindrical shell 208. Each of the gears 224 is in mesh with a pinion 225. The pinions are mounted upon a series of vertical shafts 226. These shafts extend downwardly into the base structure of the machine and are rotatably supported by bearings 227 and 228. Secured upon each of the shafts 226 at a point within the base structure is a pinion 229. These pinions, as shown in Fig. 3 of the drawing, are spaced an equal distance apart so that intermediate pinions 230 may be in mesh with the pinions 229 on each side thereof. This provides a gear train which will cause all of the pinions 229 to rotate in the same direction when driven from one of the gears. As shown in Fig. 3 of the drawing, the intermediate pinion 230 is in mesh with a large driving gear 231. This gear is fixed upon shaft 53 upon which the Geneva gear 52 is also fixed, said shaft and gear being rotated by rotation of said Geneva gear. The gear ratio is such as to insure that at each movement of the Geneva gear 52 the gear train, comprising gears 229 and 230, will rotate one-half a revolution. This in turn will alternately dispose the measuring cylinders 214 and 215 into register with the valve port 212 and the discharge nozzle 223.

In order to eject ice cream from the cylinder 214 or 215 which is in register with the valve port 212 a rocker arm 232 is provided for each of the dispensing units. These rocker arms are mounted upon standards 233. The standards 233 are secured to the base and extend upwardly therefrom to carry a rocker arm shaft 234. In Fig. 5 of the drawing it will be seen that an actuating arm 235 is fixed on the shaft 234 and is pivotally connected at 236 with a pitman rod 237. The lower end of this rod is connected to a fitting 238 by a pivot pin 239. This fitting has a threaded bore in its lower end to receive the upper threaded end 240 of a lift rod 241. The lift

rod is provided with an adjusting nut 242 which makes it possible to vary the effective length of the lift rod and to thus control the length of travel of the pistons 216. The lift rod 241 is reciprocably mounted in bearings 243 and 244 so that the rod may move vertically. A fitting 245 is secured upon the lift rod 241 and is connected to a link 246 by a pivot 247. The upper end of the link 246 is provided with a pivot pin 248 which connects with one arm of a bell crank 249. The bell crank is mounted on brackets 250 within the base structure upon a pivot shaft 251. The opposite arm of the bell crank extends downwardly and carries a cam roller 252 which rests against the surface contour of a cam 253. This cam is fixed on a timing shaft 93 which extends throughout the length of the machine and journals in bearings 94 and 95. Shaft 93 also extends through the gear box 46 and journals in suitable bearings provided on the walls thereof. This shaft has fixed thereon a gear 182 (Fig. 2) which meshes with the worm 50 on the shaft 44 so as to constantly rotate the shaft 93 while the machine is in operation.

It is to be pointed out that the run of conveyor chain 22 which passes beneath the discharge spouts 223 are led between a pair of spaced side rails 254 and 255. These temporarily close the opposite sides of the molds 75 and in effect provide in each of said molds a rectangular form within which the carton is confined while traveling beneath the filling units 20.

For a comprehensive description of the entire machine shown in the drawings of this application, reference is had to my U. S. Letters Patent No. 2,500,922 aforesaid. That description points out how blanks 10 are formed into containers C, the latter being placed in the molds 75 prior to these molds being carried by the chain 22 into position beneath the four dispensing units 20 and how the chain 22 is caused to pause with said containers so positioned while the dispensing units 20 function to fill said containers with ice cream. This intermittent driving of the chain 22 is accomplished by the rack mechanism illustrated at the extreme left end of Fig. 3. In this mechanism the gear 55 rotates continuously and the rack 58 is reciprocated by such rotation and causes the disc 61 to successively rotate in opposite directions. This disc idles past the latch 64 when rotating in a clockwise direction and engages said latch with the shoulder 62 when rotating in a counterclockwise direction. Thus the chain 22 is caused to travel during the counterclockwise rotation of the disc 61 and to pause during the clockwise rotation of said disc.

During each of such pauses four of the molds 75, each carrying an empty ice cream container C, are located under the four dispensing units 20 and in alignment respectively with the filling spouts 223 of said units. During each travel period of the chain 22, the pin 51' is disposed in one of the radial slots of the Geneva wheel 52 and this Geneva wheel is thus being rotated a quarter turn which is transmitted through the gear 231 to the shafts 226 and from these through the gears 225 to the dispensing unit rotors 213. Thus, during each period of movement of the chain 22, each of the rotors 213 is given a $\frac{1}{2}$ revolution which begins and ends with one of the measuring cylinders 214 and 215 aligned with the port 211 and with the other of said cylinders aligned with the port 212.

The piston in the measuring cylinder which is in

its down position as shown in Fig. 4 and the presence of ice cream under pressure at all times in the manifold 219 and lateral connections 220 results in said ice cream flowing upwardly into the cylinders aligned with ports 211 until the pistons 216 in said cylinders are raised into contact with the threaded packing glands 218 which close the upper ends of the cylinders. This, of course, extends the piston rods 217 connected with said pistons to their uppermost positions.

Thus, measuring cylinders which with each half rotation of the rotors 213 are brought into alignment with the ports 212 have during the immediately preceding pause in the travel of the chain 22 been aligned with the ports 211 and have thus been filled with ice cream.

The pistons 216 and piston rods 217 of these cylinders are thus in their raised positions with the upper ends of the rods just beneath the extremities of the arms 232. The cam 253 on the cam shaft 93 is so timed that during each pause in the rotation of the rotors 213 this cam elevates the cam follower 249 and through this rocks the shaft 234 causing the arms 232 to swing downwardly and depress the piston rods 217 aligned with these arms so as to empty the ice cream from the cylinders aligned with the ports 212 through the discharge nozzles 223 and into the paper containers C occupying the molds 75 aligned with said nozzles.

This operation terminates with the pistons 216 in the cylinders over the ports 212 being in their lower positions as shown in Fig. 5 while the pistons in the cylinders aligned with the ports 211 have been raised to their upper positions incidental to said latter cylinders being filled with charges of ice cream. As the cam 253 continues to rotate with the shaft 93, shaft 234 is reversely rocked so as to swing the arms 232 upwardly above the uppermost positions of the piston rods 217, and with the next movement period of the chain 22 and half rotation of the valve rotors 213, the relative positions of the measuring cylinders 214 and 215 are reversed in readiness for the ice cream dispensing operation to follow as soon as chain 22 is moved a distance sufficient to remove the four molds 75 just previously beneath the units 20 and bring the next succeeding four molds and the formed containers C occupying these, beneath said units and in alignment with the discharge nozzles 223.

It is to be noted that the quantity of ice cream or other liquid material which the invention is employed to dispense, may be delivered in varying quantities, this variation being controllable either by screwing the packing glands 218 different amounts into the upper ends of the cylinders 214 and 215 or by varying the length of the distance between the pivots 236 and 247 by screwing the threaded end 240 of the rod 241 varying distances into the fitting 238. Either of these variations would alter the volume of the charge of liquid delivered from one of the cylinders 214 or 215 in the dispensing step of the operation of the units 20. Varying the screwed-in position of a packing gland 218 in any cylinder 214 or 215 varies the amount of ice cream or other liquid which this particular cylinder will receive when aligned with one of the ports 211 whereas varying the distance between the pivots 236 and 247 varies the amount of ice cream or other liquid which is delivered from each of the four cylinders aligned with the ports 212 during a dispensing step.

The amount of liquid which is delivered from each of the cylinders in a dispensing step of the operation of the invention will vary in accordance with the amount of liquid with which said cylinder had previously been charged. From this it is seen that I have provided a means for equalizing the amounts of liquid delivered from the different cylinders 214 and 215 as well as providing a means for increasing or decreasing at will the individual quantity thus uniformly delivered from all of said cylinders.

While the present invention was developed particularly for dispensing uniform quantities of ice cream to folded paper containers for packaging said ice cream, it is to be understood that the invention may be modified by those skilled in the art in adapting it to a wide variety of uses without departing from the spirit of the invention or the scope of the appended claims.

Having thus described my invention, what I claim and desire to secure by Letters Patent is:

1. In a packaging machine, a measuring and dispensing unit beneath which a package is placed for receiving fluid material, a plate disposed horizontally and beneath which said container may be placed, a cylindrical shell extending upwardly from said plate, a valve rotor rotating within the shell and resting upon said plate, a plurality of longitudinally extending measuring cylinders formed through the valve rotor and disposed eccentrically of the rotating axis of the valve rotor, a fluid intake opening through said plate and with which said measuring cylinders may register, a fluid discharge opening through said plate and with which said measuring cylinders may move to register, a container, being adapted to be disposed below said discharge opening, means for intermittently rotating said valve rotor to successively move the measuring cylinders to the fluid intake opening and the fluid discharge opening, a plunger in the upper end of each of said cylinders and forming a fluid seal with the walls thereof, a plunger rod extending upwardly from each plunger to a point above the level of the top of the valve rotor and its shell, an operating lever overhanging the valve rotor and its shell and beneath and with which the plunger rods register when the measuring cylinders register with the fluid discharge opening, means for oscillating said lever, and synchronous driving means for alternately and intermittently operating the rotor rotating means and the lever oscillating means.

2. In a packaging machine, a measuring and dispensing unit beneath which a package is placed for receiving fluid material, a plate disposed horizontally and beneath which said container may be placed, a cylindrical shell extending upwardly from said plate, a valve rotor rotating within the shell and resting upon said plate, a plurality of longitudinally extending measuring cylinders formed through the valve rotor and disposed eccentrically of the rotating axis of the valve rotor, a fluid intake opening through said plate and with which said measuring cylinders may register, a fluid discharge opening through said plate and with which said measuring cylinders may move to register, a container, being adapted to be disposed below said discharge opening, means for intermittently rotating said valve rotor to successively move the measuring cylinders to register with the fluid intake opening and the fluid discharge opening, a plunger in the upper end of each of said cylinders and forming a fluid seal with the walls thereof, a

plunger rod extending upwardly from each plunger to a point above the level of the top of the valve rotor and its shell, an operating lever overhanging the valve rotor and its shell and beneath and with which the plunger rods register when the respective measuring cylinders register with the fluid discharge opening, a lift rod connected with said lever, a cam engaging the lift rod to cause it to reciprocate and oscillate said lever, adjustable means at a point between the cam and the plunger whereby the operating stroke of the plunger may be set to cause a measured quantity of fluid to be discharged from a measuring cylinder at one stroke of the plunger, and synchronous driving means for said cam and for the driving means of the rotating valve rotor whereby said valve rotor may be moved to bring its measuring cylinders in registry successively with the fluid inlet opening and the fluid discharge opening whereby during an intermediate period the valve plunger of the cylinder in register with the discharge opening will be forced downwardly.

3. In a packaging machine, a package conveying device by which packages are intermittently moved to a filling station, a rotatable rotor disposed thereabove, a plate between said device and said rotor and slidably fitting the latter, a pair of longitudinal cylindrical chambers in said rotor, there being a pair of openings in said plate with which said cylindrical chambers successively register, one of said openings being at the filling station, a conduit in communication with the other of said openings through which fluid to be dispensed is delivered under pressure, plungers in each of said cylindrical chambers and adapted to reciprocate upwardly under the pressure of the fluid from the conduit, and mechanical means for moving a plunger in one of said chambers downwardly at the filling station to eject the fluid from said chamber.

4. The structure of claim 3 including means for adjusting the stroke of the plunger which is acting to discharge the fluid whereby measured quantities of the fluid will be discharged.
5. The structure of claim 3, including a packing gland screwed into the upper end of each of said chambers, the vertical position of said gland determining the upper position of the plunger in said chamber when lifted by said fluid, and therefore the amount of said fluid admitted to said chamber at one time through the opening communicating with said conduit.
6. The structure of claim 3, including a packing gland screwed into the upper end of each of said chambers, the vertical position of said gland determining the upper position of the plunger in said chamber when lifted by said fluid, and therefore the amount of said fluid admitted to said chamber at one time through the opening communicating with said conduit, a variation in the amount of fluid so admitted into said chamber operating to correspondingly vary the amount of fluid discharged therefrom by said mechanical means moving the plunger in said chamber downward to a given level; and a device for adjusting said mechanical means to vary the level downward to which said mechanical means successively moves said plungers.
